UNITED STATES PATENT OFFICE.

OTTO J. YOUNGMAN, OF BERKELEY, CALIFORNIA, ASSIGNOR OF ONE-HALF TO JOHN B. HOOKSTRA, OF BERKELEY, CALIFORNIA.

DESIGN FOR A PIANO.

50,707.

Specification for Design.

Patented May 1, 1917.

Application filed February 7, 1917. Serial No. 147,249. Term of patent 14 years.

To all whom it may concern:

Be it known that I, OTTO J. YOUNGMAN, a citizen of the United States, residing at Berkeley, in the county of Alameda and State of California, have invented a new, original, and ornamental Design for a Piano, of which the following is a specification, reference being had to the accompanying drawing, forming part thereof.

In the drawing:—

Figure 1 is a front elevation of a piano, illustrating my new design.

Fig. 2 is a side elevation thereof.

What I claim is:—

The new and ornamental design for a piano, substantially as shown.

In testimony whereof, I have hereunto set my hand this 26th day of January 1917, in the presence of the two subscribed witnesses.

OTTO J. YOUNGMAN.

Witnesses:

J. B. HOOKSTRA,
C. P. GRIFFIN.
